(57) **CLAIM**

The ornamental design for an article support clip, as shown and described.

DESCRIPTION

FIG. 1 is a front elevational view of an embodiment of the present invention;

FIG. 2 is a top end view thereof;

FIG. 3 is a bottom view thereof;

FIG. 4 is a rear elevational thereof;

FIG. 5 is a right side elevational view thereof; and,

FIG. 6 is a left side elevational view thereof.

The broken lines represent portions of the design that form no part of the claim.
